UNITED STATES PATENT OFFICE

HENRI A. SÉVIGNÉ, OF WINTHROP, MASSACHUSETTS, AND CHARLES E. JACOBS, OF NASHUA, NEW HAMPSHIRE, ASSIGNEES TO NATIONAL BREAD WRAPPING MACHINE COMPANY, OF BOSTON, MASSACHUSETTS, A CORPORATION OF MASSACHUSETTS

WRAPPING MACHINE

Application filed April 21, 1927. Serial No. 185,496.

This invention relates to machines for wrapping articles such as loaves of bread or cake, and has particular reference to machines of the type illustrated in Letters Patent No. 1,412,754 issued April 11, 1922 upon an application filed by Sévigné and Arnold.

As illustrated by Figures 26 to 34 of said patent, the operation of that machine resulted in assembling a loaf and a wrapping with the top of the loaf in contact with the middle portion of the wrapper, then simultaneously folding the wrapper against two opposite sides of the loaf with edge portions of the wrapper projecting substantially equally beyond the plane of the bottom of the loaf, then simultaneously folding side edge portions of the wrapper against the ends of the loaf to form outstanding corner folds, then folding said corner folds in overlapping position against the ends of the loaf, and then successively turning in different edge portions of the wrapper and overlapping them against said bottom of the loaf with a single final flap or edge portion overlying all other turned in edge portions.

While the form of fold just described is largely employed, some bakers prefer what is known as an end fold or wrap; that is, a form of fold wherein the final folding and sealing is effected at the ends of the loaf instead of at the bottom thereof.

One of the objects of the present invention is to provide an improved machine which, while similar in many respects to that of the patent referred to, automatically and rapidly encloses the articles in wrappers having final sealed folds at the ends thereof instead of the bottom.

Another object is to provide a wrapping machine which not only measures the length of each wrapper section according to the size of each loaf to be wrapped therein as is done by the machine of the said patent referred to, but also enables a web of paper to be employed for the wrappers which web is much narrower than that employed in the machines of said patent, the result being that the present improved machine not only uses wrapper sections of minimum length to reach around the loaves, regardless of the height thereof, but

also of minimum width. This last is due to the fact that in the present improved machine the web of wrapping material is not, and does not need to be, wide enough to permit any side edge portions thereof to not only extend down the ends of the loaf but also reach under the bottom of the loaf.

With the above-stated objects in view, and others hereinafter described, the invention consists in the construction and combination of parts substantially as hereinafter recited and claimed.

Of the accompanying drawings:

Figure 1 is a side elevation, with parts broken out or in section, and including those features which relate to the present invention.

Figure 2 is a plan view of the same.

Figure 3 is a perspective view, looking in the direction of the arrow 3 adjacent to Figure 2, and omitting some parts of the machine the illustration of which would confuse the figure.

Figure 4 represents a detail section on line 4-4 of Figure 2.

Figures 5, 6, 7 and 8 are views illustrating the successive steps of the wrapping operation.

Similar reference characters indicate similar parts or features in all of the views.

We will first briefly describe some of the parts of the present machine which are the same, or substantially the same, as in the Patent No. 1,412,754, although the reference characters employed herein are not the same as in said patent.

Portions of the frame of the machine are indicated at 25. From a supply roll mounted on a frame-supported core or shaft, the web of paper P passes under tension rolls or rods 27, then over a feed drum 28 with which upper rolls 29 cooperate to feed the web over a bed or table 30 a greater or lesser distance according to the size of each loaf to be wrapped in a section which is cut off from the web by a knife 31. The variation in the length of feed or advance of the web before it is cut, is controlled by the feeler 37 presently referred to.

The loaves pass down a gravity slideway

32 onto a horizontal bed 33 and against a stop wall 34, and are successively fed in over the bed 33, by one of the series of pushers 35, to position for the commencement of the wrapping operation.

5 Each loaf is then raised by one of a series of lifting fingers 36 moving upwardly through a vertical chute or passageway, and said loaf, when so moving, carries with it a 10 wrapper section which is thereby draped over the loaf. Each loaf, when first moved in over the bed 33 by a pusher 35, passes under a feeler 37 carried by a lever 38 which lever, by mechanism described in the patent referred to and illustrated by Figures 7 to 12 15 thereof, controls the length of advance or feed of the web by the drum 28 and rolls 29 so that the length of the section cut off by the knife 31 will be only such as to sufficiently 20 but economically surround the loaf of that particular size.

The bed 30 has horizontal extensions over which the side margins of the paper ride just before the knife 31 operates. The lifting fingers 36 and the loaf elevated thereby pass up between said extensions, and the paper section is draped over the loaf. As the loaf and wrapper section continue to rise, they pass between two primary end folders 40 25 justably mounted on fixed brackets 41. Said folders act upon the wrapper to fold it to the position illustrated by Figure 5, such action being substantially the same as that performed by similar primary folders of the 30 patent hereinbefore mentioned.

40 Secondary folders 42, one at each side of the vertical passageway, are attached to and carried by the fixed plate 43 forming one wall of said passageway, and a third pair of folders 44 are mounted as hereinafter described. The edges of the folders 42, 44, are so shaped, somewhat helically, as to effect, during the upward movement of the loaf and wrapper section, a folding of the wrapper to 45 the form illustrated by Figure 6.

As so far described, the machine is the same as, or closely similar to, the machine of the Patent No. 1,412,754. In said patent the structure was such that the wrapper employed 50 was necessarily of sufficient width to enable edges of the folded portions herein illustrated at *a* in Figure 5, to be folded somewhat under the bottom of the loaf. Important features of the present improved machine 55 are the mechanisms which will now be described and which effect end folding as illustrated by Figures 7 and 8.

As the partially enclosed loaf (Fig. 6) rises and reaches its uppermost position in 60 the vertical passageway, and just before the lifting fingers drop down away from it in the manner explained in said Patent No. 1,412,754, two end pressers 45 (Figs. 1 and 2) having horizontal face ribs 45', move in toward each other and hold the loaf. Then a

70 folder blade 46 (Figs. 1, 2 and 3) swings in and folds the wrapper portion *b* (Fig. 6) in under the bottom of the loaf, and immediately thereafter a folder blade 47 acts to fold the wrapper portion *b'* in under the loaf to partly overlap the portion *b*. This results in the wrapper assuming the form illustrated by Figure 7, with the overlapped and tapered portions of the end or corner folds projecting outwardly under the lower edges of the 75 end pressers 45. As illustrated by Figure 1, spaces are provided below the edges of the pressers to enable the corner folds to project as just described.

75 The mechanism for operating the pressing and folding devices just mentioned will now be described.

80 Each end presser 45 has its shank 48 mounted in a slideway 49 carried by the frame of the machine, and is operated by an elbow lever 50 pivoted at 51 and having a 85 roll which is acted upon by a cam 52 carried by the shaft 53 (Fig. 3). By means of suitable springs not necessary to illustrate, the end pressers 45 act yieldingly against the 90 loaf.

95 The folder blade 46 is mounted on a bar 54 carried by two arms 55 of a rock shaft 56 having, at one end, an arm 57 provided with a roll engaging a path cam 58 carried by the 100 shaft 53 (Fig. 1).

105 The folder 47 has end blocks 59 mounted in horizontal slideways 60 at opposite sides of the frame of the machine (Figs. 2, 3 and 4). Each slideway 60 has a shank 61 mounted in a vertical slideway 62 fixed to the frame of the machine. This is in order that the folder 47 may have a vertical movement to effect upward pressure against the bottom 110 of the loaf. To effect this movement, each shank 61 has a roll 63 riding on a cam 64 carried by a shaft 65. To reciprocate said folder 47 to cause it to advance under the loaf and then retreat, each horizontally slidable block 59 is connected by a link 66 with an arm 67 of a rock shaft 68 mounted in the frame of the machine and having at one end an arm 69 connected by a link 70 with the upper 115 end of a lever 71 pivoted on shaft 56, the lower end of said lever 71 having a roll 72 riding on a cam 73 carried by the shaft 53.

120 The mechanism just described actuates the folder 47 in an advancing path while lowered, then upwardly and then backwardly, and the timing of its operation is such that as the other transverse folder 46 acts on the wrapper flap *b* (Fig. 6) to tuck it under the loaf, the said folder 47 moves under the loaf while in a lowered plane due to the lowered 125 vertical movement of the horizontal slideways 60, and while so moving under the loaf flexes the wrapper flap *b'*, and then moves upwardly and completely folds said flap *b'* up against and partly overlapping the flap *b*. This structure ensures such spacing of 130

the tucker or folder 47 from the bottom of the loaf that the forward edge of said folder has practically no tendency to tear the wrapper when moving under the loaf. During this 5 movement the corner folds *c c* are formed, with their tapered tips extending outwardly. The folder 47 then retreats and drops to lowered position ready for the next advance folding movement. Before such retreat of the 10 folder 47, and while both of the tucking or folding members 46, 47, are in their inward positions over the top of the vertical passageway, the loaves are moved laterally by the pushers 74 as presently described, and therefore 15 said members 46, 47, act as a temporary bridge or floor for the loaves to support them as they are moved along, so that a loaf can not so tilt back into the top of the passageway that it would catch against the top of the 20 wall plate 79 and be crushed. In other words, each loaf will be slid smoothly along over the temporary bridge afforded by the members 46, 47, when acted upon by a pusher 74.

25 The completion of the end folding is effected while the loaf, in the wrapped condition illustrated by Figure 7, is being pushed horizontally by one of the pushers 74 carried by chains 75 similar to mechanism of the 30 patent hereinbefore referred to. When a pusher 74 moves the enclosed loaf along over the folder plate 47, the outwardly extending tapered tips of the end corner folds *c c* pass into, and are turned up by, the upwardly inclined crevices *x* (Fig. 1) between the rear inclined edges of the pressers 45 and the inclined edges of plates or fingers 76 extending from side heaters 77 (Fig. 2), said inclined crevices serving to complete the end folds as 35 illustrated by Figure 8. The reason for the ribs 45' on the inner faces of the end pressers 45 is that since the said pressers are bearing against the ends of the loaf while a pusher 74 is moving it horizontally, said ribs serve 40 as guides to prevent the loaf from tilting as it is transferred in horizontal direction. Without said ribs, the loaf would tilt or drop as the outwardly projecting corner flaps or folds illustrated by Figure 7 commence being turned up into the inclined crevices *x*. 45

As the completely wrapped loaf is moved along by a pusher 74, its end folds are sealed by the action of the heaters 77, preferably electrical heaters, the wrapping material being, as usual, waxed paper. And its bottom overlapping edge portions are similarly sealed by the action of a horizontal heater 78 (Fig. 2):

50 Returning now to the vertical passageway through which the loaves are successively elevated by the lifting fingers 36, it will be seen that the inner wall of said passageway consists of a plate 79 which carries the folder helixes 44 (Fig. 1). Said plate is mounted 55 to be yieldable relatively to the opposite or outer wall plate 43, and is also actuated to be swung in proper timing by mechanism presently described. Said plate has a pair of studs 80 projecting from its rear face, near its lower edge, said studs passing through holes in a fixed transverse bar 81 carried by frame brackets 82. Springs 83 coiled around the studs 80 permit the yielding movement above mentioned. Projecting rearwardly from the upper portion of the plate 79 is a 60 stud 84, said stud passing through a hole in an ear 85 of a pitman 86 slidably mounted or guided on the shaft 87 and having a roll 88 engaging a face cam 89 indicated by dotted lines in Figure 1. A spring 90 is coiled around the stud 84, said spring cooperating with the springs 83 above referred to in permitting the wall plate 79 to bear yieldingly against any upwardly moving loaf which may have a top portion wider than the regulation width of the pan in which it was baked. 65

The timing of operation of the wall-plate-actuating cam 89 is such as to swing said plate back just as the loaf reaches its uppermost position in the vertical passageway and is gripped by the two end pressers 45, and the lifting fingers 36 are about to drop down away from the loaf. This will be readily understood by assuming that a loaf, in the wrapped condition illustrated by Figure 7, is present in Figure 1 in the plane of, and held momentarily by, the end pressers 45. At this time that one of the endless series of lifters 36 which elevated the loaf to the position just assumed, swings down to the tilted position shown in said Figure 1 in the same manner as explained in the Patent No. 1,412,754 and illustrated by Figure 4 of that patent. During this movement, the fingers swing from the horizontal plane which they have while lifting the loaf, to a downwardly inclined plane just prior to moving over or back to their downward return path of travel. This swinging movement causes the tips of the said lifting fingers to describe an arc. Now, owing to the swinging movement of the yieldable rear wall plate 79 back to the position illustrated in Figure 1, a space is briefly provided to enable said fingers, which are longer than in the machine of the patent referred to, to describe or move in said arc without contacting with the face of said wall plate 79. The object of drawing or swinging the plate 79 back momentarily as has been described is to enable the lifting fingers 36 to have such length as to reach substantially across the entire width of the bottom of each loaf when performing the lifting operation, such length of reach materially reducing liability of a loaf tilting over during its upward movement through the vertical passageway. The timing of oscillations of the wall plate 79 is such that immediately after the lifting fingers have cleared it when dropping down from a loaf and started over for 130

its return downward travel, said wall plate is returned by the cam 89 to vertical position parallel with the other wall plate 43, to properly guide the loaf which is being elevated

5 by the next of the endless series of lifters 36.

Having now described our invention, we claim:

1. A wrapping machine comprising means for assembling a loaf and a wrapper with 10 the top of the loaf in contact with the middle portion of the wrapper, means for then simultaneously folding the wrapper against two opposite sides of the loaf with edge portions of the wrapper projecting substantially 15 equally beyond the plane of the bottom of the loaf, means for then simultaneously folding intermediate side edge portions of the wrapper down against the ends of the loaf to form outstanding corner folds, means for 20 then folding said corner folds in overlapping position against the ends of the loaf, means for then folding transverse edge portions of the wrapper against the bottom of the loaf, and means for then folding portions of the 25 overlapped corner folds up against the ends of the loaf.

2. A machine substantially as specified in claim 1 and having means for applying heat to the bottom and ends of the wrapped loaf.

3. In a wrapping machine, the combination with wrapping mechanism, of means for feeding wrapping material, means actuated by the passage of an article to be wrapped for operating said feeding mechanism, said 35 operating mechanism including means for proportioning the size of the wrapper to the size of said article, and means for folding all side edge portions of the wrapper against the ends of the article.

4. A wrapping machine having feeding mechanism for a web of wrapper material, a cutter for severing the web into sheets, folders for inclosing each article in a wrapper sheet with the corner portions of said sheet overlapped and folded up against the ends of the article, and means controlled by the passage of each article on its way to be assembled with its wrapping sheet for determining the 45 operation of the feeding mechanism and cutting according to the size of said passing and controlling article.

5. In a wrapping machine, a vertical passageway having successively operating folders therein, means for elevating articles successively past said folders, pressers above said passageway for temporarily engaging the ends of each article, said pressers having horizontal ribs and spaces being provided below the lower edges of the pressers to permit folded portions of the wrappers to extend out below said edges, and means for pushing the article laterally from between said pressers while guided by said ribs.

6. In a wrapping machine having means 65 for enclosing each article in a wrapper, a

movable folder, and means for imparting thereto a substantially four-motion path of movement relatively to the bottom of the article.

7. In a wrapping machine having means 70 for enclosing each article in a wrapper with edge portions of the wrapper at the bottom of the article, a movable folder, and means for imparting thereto a substantially four-motion path of movement relatively to the 75 bottom of the article.

8. In a wrapping machine having means for enclosing each article in a wrapper with edge portions of the wrapper at the bottom of the article, a folder plate having a substantially four-motion path of movement relatively to the bottom of the article, and means for pushing the wrapped article over said plate toward the delivery end of the machine. 80

9. In a wrapping machine, a vertical passageway having successively operating folders therein, means for elevating articles through said passageway, folder plates movable toward and from each other across the top of the said passageway, and means for 90 imparting to one of said plates a path of movement to cause it to advance while lowered, to then rise, and then retreat.

10. In a wrapping machine, a stationary plate and a yielding plate adapted to form 95 the sides of a vertical passageway, a series of carriers adapted to transport articles successively through said passageway, wrapper folding mechanism in said passageway, and means for intermittently oscillating the said 100 yielding plate.

11. In a wrapping machine, a vertical passageway having opposite wall plates one of which is provided with means for intermittently oscillating it relatively to the other plate, wrapper folders adjacent to side edges of said plates, and means for elevating articles successively through said passageway. 105

12. In a wrapping machine, a pair of wall members relatively located to provide a vertical passageway, article-lifting fingers movable upwardly through said passageway, said fingers being mounted to swing downwardly when they reach the upper end of the passageway, means for folding portions of the wrappers while being lifted, and means for momentarily retracting one of said wall members to avoid contact of said fingers therewith when swinging downwardly. 110

13. In a wrapping machine, a pair of plates relatively located to provide walls of a vertical passageway, an endless series of article-lifting fingers movable upwardly through said passageway, said fingers being mounted to swing downwardly when they reach the upper end of the passageway, means for folding portions of the wrappers while being lifted, and means for momentarily retracting one of said plates to widen the space between 115 120 125 130

the two plates when said lifting fingers swing downwardly.

14. In a wrapping machine, means for elevating an article and a wrapper draped thereover, means for partially folding the wrapper while being elevated, means for tucking opposite transverse edge portions of the wrapper in opposite directions under the article while raised, one of said tucking means being movable in a path to cause it to advance while lowered, to then rise and then retreat, and means for then folding side edge portions of the wrapper against the ends of the article.

15. In a wrapping machine, means for elevating an article and a wrapper draped thereover, means for partially folding the wrapper while being elevated, means for tucking opposite transverse edge portions of the wrapper in opposite directions under the article while raised, one of said tucking members having means for moving it under the article and then upward toward said article, means for moving the article and its wrapper laterally on and over the last-mentioned tucking member while the latter is raised, and means for folding side edge portions of the wrapper up against the ends of the article.

In testimony whereof we have affixed our signatures.

30 HENRI A. SÉVIGNÉ.
CHARLES E. JACOBS.
